(57) **CLAIM**

The ornamental design for a dual lens magnifier camera, as shown and described.

DESCRIPTION

FIG. 1 is a top, front and right side perspective view of a dual lens magnifier camera showing my new design;

FIG. 2 is a bottom, back and left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the encircled portion in FIG. 1; and,

FIG. 10 is an enlarged view of the encircled portion in FIG. 2.

The broken lines depict portions of the dual lens magnifier camera in which the design is embodied that form no part of the claimed design. Additionally, the dot-dash broken lines encircling an enlargement portion of the design forms no part of the claimed design.
